UNITED STATES PATENT OFFICE.

OTIS D. PARKER, OF PORTSMOUTH, VIRGINIA.

CAR-DOOR LOCK.

Application filed July 13, 1925. Serial No. 43,334.

To all whom it may concern:

Be it known that I, OTIS D. PARKER, a citizen of the United States, residing at Portsmouth, in the county of Norfolk and State of Virginia, have invented new and useful Improvements in Car-Door Locks, of which the following is a specification.

This invention relates to locking devices for the sliding doors of railway freight cars and has for its object the provision of a novel device which will hold the door in locked position and which will replace the usual hasp structure commonly used at the present time.

An important object is the provision of a locking device of this character which is provided with a movable element normally engaging behind the rear edge of the door at the lower corner thereof for holding the door firmly in its closed position, the holding element being swingable into release position whereby the door may be opened when desired.

Another object is the provision of a locking device of this character which is provided with means whereby a seal of ordinary construction may be placed in position, the seal of course, if broken, indicating that the lock has been tampered with by an unauthorized person.

Another object of the invention is to provide a locking device of this character which will keep the door stiles from pulling off and which will also keep the lock rails from bursting to pieces, and which will moreover effectually brace and strengthen the door structure so that it will naturally have a longer life than is ordinarily the case.

An additional object is the provision of a device of this character which will be simple and inexpensive in manufacture, easy to install, positive in action, efficient and durable in service, and a general improvement in the art.

With the above and other objects and advantages in view, the invention consists in the details of construction and the arrangement and combination of parts to be hereinafter more fully described and claimed, and illustrated in the accompanying drawings, in which:

Figure 1 is a fragmentary side elevation of a car showing the lock applied and in its locked or operative position holding the door.

Figure 2 is a horizontal section through

the door and a portion of the car showing a plan view of the locking device.

Figure 3 is a view of the locking device alone showing the movable member swung into releasing or inoperative position permitting the door to be opened.

Figure 4 is a fragmentary vertical section through the door showing an end elevation of the locking device, and

Figure 5 is a detail section taken substantially on the line 5—5 of Figure 1.

Referring more particularly to the drawings, the letter A designates a portion of a freight car including the usual side sill B to which the siding C is secured. The letter D designates the usual sliding door which is mounted in the customary manner and which is capable of being moved back and forth to cover or uncover the door opening in the usual manner.

In carrying out the invention, I provide a locking device or mechanism including a supporting member designated generally by the numeral 10 and formed preferably as a casting. This supporting member includes a base or plate portion 11 from which extends a projecting portion 12. The portions 11 and 12 are in the same plane and provide means for securing the device in place, these portions being apertured for the passage of

suitable bolts 13 which have their heads located at the outside of the car and which therefore cannot be removed from the outside, hence making the device burglar-proof. The supporting member 10 further includes a horizontally extending shelf or ledge portion 14 which is slotted throughout the major portion of its length as indicated

at 15 for a purpose to be described, and at the ends of the member 10 are webs 16 formed integrally with the shelf or ledge and with the plate portion 11 so as to provide a strong and rigid structure. At an intermediate portion, the member 10 is formed

with a block-like wall 17 recessed as indicated at 18, this recess registering with the slot 15 in the shelf or ledge. On the underside of the shelf or ledge is a projection 19 for a purpose to be described.

The door engaging and holding member comprises an angular arm 20 which may like-wise be formed as a casting and which includes a reduced or shank portion 21 extending through the slot 15 and pivoted within the recess 18 as indicated at 22. This pivot is preferably an elongated bolt which

passes not only through the bracket member 10 but through the side sill of the car, the head being located at the outside thereof in order to prevent removal by an unauthorized 5 person. The arm 20 terminates in a head 23 having a depending portion 24 extending outwardly of the adjacent web 16 at the end of the bracket support 10. The head is further formed with a flat surface 25 adapted to 10 bear against the rear edge of the car door D at the lower corner thereof and is formed with an overhanging flange 26 which will extend outwardly of the door and prevent the same from being swung or otherwise 15 moved outwardly away from the side of the car as will be readily apparent. The construction and mounting of the arm 20 are such that when the arm is swung away from the car door the shank portion 21 will move 20 through the slot 15 and be accommodated within a slot 27 in the end web 16 most remote from the door. When in this position it is obvious that the head 23 will be disposed in a plane sufficiently low that even the projection 24 will be located at a point slightly 25 beneath the level of the shelf or ledge 14 so as to be in non-obstructing relation to the door, thus permitting the door to be slid into its open position in the usual manner. 30 For effecting locking of the arm member 20 I preferably provide a bolt or pin 28 slideable through a suitable hole 29 in the web 16 nearest the door and slideable through a bore or hole 30 in the projection 19. The 35 bore 30 is of peculiar formation inasmuch as there are two substantially opposite projections or ribs 31 which extend inwardly and which cooperate with portions of the bolt or pin for the purpose of holding the latter against rotation. This pin or bolt is projectible through a suitable hole or opening 32 in the projection 24 of the locking arm so as to hold this arm positively against 40 swinging movement into its door releasing position. The bolt or pin 28 and the projection 24 are formed with registering slots 33 and 34 respectively through which may be passed a seal 35 of ordinary construction. Obviously, the bolt or pin can not be retracted to release the locking arm unless this 45 seal be broken. As the seal is located in a low position it is more convenient to apply and read. 50 From the foregoing description and a 55 study of the drawings, it will be apparent that I have thus provided a simply constructed, easily installed and easily operated or controlled locking device for sliding doors of freight cars. Attention is invited to the 60 fact that when the lock is in its operative or door holding position a portion of the end bears flat against the rear edge of the door for holding it against the opposite jamb while a portion overlies the door so as to hold 65 it against the side of the car and prevent it

from being moved away therefrom. Ample provision has been made for locking the door holding arm in position and imparting a usual seal, destruction of which would of course indicate that the car had been tampered with. It is believed that the construction, operation and advantages will be readily apparent to one skilled in the art without further explanation. 70

While I have shown and described the preferred embodiment of the invention, it should be understood that I reserve the right to make such changes in the form, construction and arrangement of parts as will not depart from the spirit of the invention or the scope 75 of the subjoined claims. 80

Having thus described the invention, I claim:—

1. A locking device for a sliding freight car door, comprising a supporting member 85 mounted upon the side of the car at the lower portion thereof, an arm member pivoted upon said support and adapted to abuttingly and overhangingly engage a portion of the door, and a bolt slidably mounted in said supporting member and engaging said arm for holding the same against movement, said arm being swingable away from the door to be disposed out of the path of movement thereof, said supporting member being 90 slotted to accommodate the release position of the arm. 95

2. A locking device for a freight car door, comprising a supporting member of bracket-like formation mounted upon the side sill 100 of the car and including a horizontal shelf portion and end web, said horizontal portion being formed with a longitudinal slot extending clear to one end, and one web being slotted in registration with said first 105 named slot, an arm extending through the first named slot and pivoted beneath the shelf portion of the supporting bracket, said arm terminating in a head having a flat face bearing against the edge of the door and 110 having a flange overlying the door. 115

3. A locking device for a freight car door, comprising a supporting member of bracket-like formation mounted upon the side sill 115 of the car and including a horizontal shelf portion and end web, said horizontal portion being formed with a longitudinal slot extending clear to one end and one web being slotted in registration with said first named slot, an arm extending through the first 120 named slot and pivoted beneath the shelf portion of the supporting bracket, said arm terminating in a head having a flat face bearing against the edge of the door and having a flange overlying the door, and a projection extending downwardly from the head and located adjacent the other web, said last named web and said projection being formed with registering holes, and a lock bolt slidably mounted beneath the shelf 125 130

portion of the supporting bracket and engageable through said holes for holding the arm against swinging movement.

4. A locking device for a freight car door, comprising a supporting member of bracket-like formation mounted upon the side sill of the car and including a horizontal shelf portion and end web, said horizontal portion being formed with a longitudinal slot extending clear to one end and one web being slotted in registration with said first named slot, an arm extending through the first named slot and pivoted beneath the shelf portion of the supporting bracket, said arm terminating in a head having a flat face bearing against the edge of the door and

having a flange overlying the door, and a projection extending downwardly from the head and located adjacent the other web, said last named web and said projection being formed with registering holes, and a lock bolt slidably mounted beneath the shelf portion of the supporting bracket and engageable through said holes for holding the arm against swinging movement, a projection beneath the shelf bored out to constitute a guide for the bolt, the bolt and said last named projection being formed with registering slots receiving a seal. 20 25

In testimony whereof I affix my signature.

OTIS D. PARKER.
